Inventor
Hans Nicolai Kjalmann
by his attorney
Louis Bagger & Co.

UNITED STATES PATENT OFFICE.

HANS N. KJALMAN, OF HYDE PARK, ILLINOIS.

SEWING-MACHINE.

SPECIFICATION forming part of Letters Patent No. 235,783, dated December 21, 1880.

Application filed April 9, 1880. (Model.)

To all whom it may concern:

Be it known that I, HANS NICOLAI KJALMAN, of Hyde Park, in the county of Cook and State of Illinois, have invented certain new and useful Improvements in Sewing-Machines; and I do hereby declare that the following is a full, clear, and exact description of the invention, which will enable others skilled in the art to which it appertains to make and use the same, reference being had to the accompanying three sheets of drawings, which form a part of this specification.

The object of my invention is to simplify the construction of shuttle-machines; and to this end it consists in certain improvements in the mechanisms for operating the shuttle-driver, the take-up device, and the cloth-presser.

In the accompanying drawings, Figure 1 is a side elevation of a sewing-machine embodying my improvements, a portion of the frame being broken away. Fig. 2 is a bottom plan. Figs. 3 and 4 represent detail views of the tubular sliding cam for operating the shuttle-driver. Fig. 5 is an end view of the goose-neck with its head removed. Fig. 6 is a perspective view of the interior of the said head with its appurtenances. Figs. 7 and 8 are perspective views representing, respectively, the lower end of the needle-bar and of the feed-bar. Fig. 9 is a perspective view of the double eccentric or cam for operating said bars. Fig. 10 is a longitudinal sectional view of the machine. Fig. 11 is a detail view of the feeding mechanism, and Fig. 12 is a vertical section through the device represented in Fig. 7.

Similar letters of reference indicate corresponding parts in all the figures.

A is the bed-plate or base, which is cast in one piece with the hollow post A' and its overhanging hollow arm or goose-neck A².

B is the driving-shaft, which is rotated by the fly-wheel pulley a, and has secured upon its front end the double eccentric or cam C.

Upon the rear end of shaft B is inserted a tubular cam, D, which has a slot, b, extending around the shaft, and curved to form a projection, d, in the upper part of the cam.

e is a stud, which is inserted permanently into the shaft and provided with a friction-roller that works in the curved slot b; and it follows that when shaft B is rotated cam D

will slide forward and back upon the shaft which is inserted through it, on account of the conformation of the slot b, the rising inclined curve of which, alike on both sides of the projection d, alternately impels the cam forward and back upon the shaft, the end of the rearward throw being reached as stud e passes the projection d.

Cam D is made with a downward-projecting wing, e, in which is pivoted the upper end or head of a lever, E, which has its fulcrum at f, inside of the hollow post A'. To the lower end of this lever is connected a pitman, F, which connects with the shuttle-driver G underneath the bed-plate.

Cam C, upon the forward end of the driving-shaft, consists of an eccentric, C', secured upon or made in one piece with a disk, C, which is provided on its front face with a wrist-pin, g, having a friction-roller, g'.

The upper enlarged part of the feed-bar H is made with an opening of the configuration shown in dotted lines in Fig. 5, so as to ride upon the eccentric C', which projects into this opening; hence when the shaft is rotated, a vibratory reciprocating motion is imparted to the feed-bar. The vibrations or throw of the lower end of this bar, which is provided with the serrated feed-shoe H', may be regulated, to regulate the length of the stitches, by means of a thumb-nut, h, which works upon a screw inserted through the downwardly-projecting slotted arm or extension I' of the inclosing-head I, and also through the slot i in the feed-bar, which rides upon the shank of the thumb-nut h, that serves as an adjustable fulcrum for the feed-bar.

The needle-bar K, which works through perpendicular tubular bearings in head I, has a slotted plate, k, affixed to it within the head, the curvilinear slot l in which plate receives the wrist-pin g with its friction-roller g'. In rotating shaft B, with its disk C, a vertical reciprocating motion is thus imparted to the needle-bar.

The take-up device consists of a short rod, L, which is inserted through an adjustable screw-threaded sleeve, M, inserted through the top part of head I. At the lower end of bar or rod L is a shoe-piece, L', which impinges upon the upper part or head of the

feed-bar H, against which it is pressed by a coiled spring, m, which is inserted (encircling rod L) into the sleeve M. The take-up lever N is hinged in the upper end of rod L, and 5 projects with its forward free end through a slot, n, in the upper part of the needle-bar, which is hollow and provided with a spiral spring, n', that bears against the under side of the take-up lever.

- 10 The lower end of the needle-bar, into which the needle is inserted and held in place by a jam-screw in the usual manner, is made tubular to receive a spiral spring, n², as shown in Figs. 7 and 12, against the lower end of which 15 the upper ends of the parallel arms of the cloth presser or holder impinge. This presser consists of a piece of doubled steel wire, O, bent at a right angle at its lower doubled end to form a projecting loop, o, through which 20 the point of the needle projects in operating the machine. The arms of the wire loop O are inserted into the tubular needle-bar, one on each side of the needle, and may be prevented from falling out by forming heads on 25 their upper ends larger than the apertures in the plug K' at the lower end of the needle-bar, through which they are inserted.

The feed-bar may be lifted up from the bed-plate upon which it works, and retained in its 30 elevated position by means of the projecting pin p, which engages with a slide, P, working in a slot or recess in the end plate, Q, of the goose-neck A², which slide P may be adjusted up or down to elevate or lower the feed-bar by 35 means of a cam-lever, R, which is pivoted upon the outside of plate Q.

From the foregoing description, taken in connection with the drawings, it will be seen that this machine consists of comparatively few 40 and simple parts, which are so constructed and combined as to operate with great ease with a minimum of friction, and to which access may readily be had, when necessary, for repair, adjustment, &c.

45 The means for adjusting the throw of the feed-bar—viz., the thumb-nut h, working through the slotted arm I' and longitudinally-slotted feed-bar—admit of considerable variation in the length of the stitch, and by the arrangement of the yielding cloth-presser O o, inserted into the end of the needle-bar, the fabric is kept down upon the bed-plate while the feeder returns and while the needle makes its loop. The thread X, after it leaves the

tension device Y, is inserted through a wire 55 eye or hook, x, projecting from the top of head I to one side of the upper end of the reciprocating needle-bar and then passed up through the loop or eye in the outer end of the take-up lever N, as shown in Fig. 1, after which it is 60 passed down to and inserted through the eye of the needle.

It will be seen that the tension of the take-up lever may be adjusted by adjusting the threaded sleeve M, the lower end of which 65 bears against spring m, which regulates or controls the pressure of bar L, with its shoe L', against the upper slotted part or head of feed-bar H, so as to compensate for wear, and also that spring n', which is inserted into the 70 tubular slotted head of the reciprocating needle-bar K, cushions the up and down strokes of the take-up lever N, thus avoiding breaking of the thread and maintaining its proper tension during the operation of the machine. 75

Having thus fully described my invention, I claim and desire to secure by Letters Patent of the United States—

1. In a sewing-machine, the combination of the driving-shaft B, having roller-stud c, tubular cam D, sliding upon said shaft and having curved slot b and wing e, lever E, pitman F, and shuttle-driver G, substantially as set forth. 80

2. In a sewing-machine, the combination of the driving-shaft B, having eccentric C', slotted feed-bar H, riding upon and operated by said eccentric, bar L, having spring m and shoe-piece L', hinged take-up lever N, and slotted tubular needle-bar K, having spring n', substantially as set forth. 85

3. The combination, with the tubular needle-bar K, having plug K', of the spring n² and cloth-presser O o, the parallel arms of which are inserted into the needle-bar through its plug K' and adapted to be depressed by 90 the spring n², substantially as set forth.

4. The needle-bar K, made hollow or tubular in both ends, slotted at n, and provided with the springs n' n², plug K', and yielding cloth-presser O o, substantially as and for the 100 purpose shown and set forth.

In testimony that I claim the foregoing as my own I have hereto affixed my signature in presence of two witnesses.

HANS NICOLAI KJALMAN.
